UNITED STATES PATENT OFFICE.

LOUIS PFINGST, OF BOSTON, MASSACHUSETTS, ASSIGNOR, BY MESNE ASSIGNMENTS, TO PFINGST ELECTRIC MANUFACTURING COMPANY, OF KITTERY, MAINE, A CORPORATION OF MAINE.

POWER-BRAKE.

No. 829,032.

Specification of Letters Patent.

Patented Aug. 21, 1906.

Application filed November 4, 1904. Renewed February 19, 1906. Serial No. 301,914.

To all whom it may concern:

Be it known that I, LOUIS PFINGST, of Dorchester, Boston, in the county of Suffolk and State of Massachusetts, have invented 5 certain new and useful Improvements in Power-Brakes, of which the following is a specification.

My invention relates to improvements in power-brakes, and especially to brakes which 10 are adapted to be applied by motive power and hand-power or by either independent of the other.

The objects of my invention are as follows: to rotate a chain-winding brake-spindle by motive power independent of the hand-power; to rotate a chain-winding brake-spindle by hand-power independent of any motive power; to rotate a chain-winding brake-spindle by the conjoint operation of 20 the motive power and hand-power; to automatically hold the taken-up chain whether the brakes are fully or partially applied either by motive power or by hand-power, or both; to provide an automatic arrangement 25 for transmitting motive power to the chain-winding brake-spindle; to provide an arrangement for automatically engaging the motor-power clutch members by an electric circuit; to provide an arrangement for cutting 30 out the clutch members' circuit by another electric circuit or by manual operation; to automatically cut in the current flowing to the motor to rotate same; to cut out said current by manual effort, so that in 35 case the motorman deserts his car for any reason the brakes will be automatically applied, and by this automatic arrangement a plurality of spindles can be set in motion to set the brakes on one or more cars. These 40 and other objects are accomplished by the mechanism hereinafter described and shown.

My invention consists of certain novel features hereinafter described, and particularly pointed out in the claims.

In the accompanying drawings, which 45 illustrate a construction embodying my invention, Figure 1 is an elevation of the device with the casing partly broken away to show the interior mechanism with certain parts in section. Fig. 2 is a cross-sectional view on the line X X, Fig. 1, and showing the brushes in contact with the commutator and also showing the in and out wires. Fig. 3 is

an enlarged detail view of the circuit-closing device for the electromagnetic clutch. Fig. 4 is a top plan view of the same. Fig. 5 is an elevation, partly in section, taken at right angles to Fig. 1, showing the brush-holding arrangement, also the pole-pieces and fields in section and the other parts in full lines. 60 Fig. 6 is a cross-section on the line X' X', Fig. 1. Fig. 7 is a cross-section on the line X² X², Fig. 1. Fig. 8 is an enlarged view in elevation and partly in section of the motor circuit-controller. Fig. 9 is an end elevation 65 and the clutch-circuit-closing device looking from the left. Fig. 10 is a top plan view of a car with the body removed and showing the platform and location of power-driven brake-spindle and brake-rigging. Fig. 11 is a side 70 elevation of the same, showing the location of the power-driven brake-spindle and brake-rigging. Fig. 12 is a diagrammatic view of wiring for a single car or a train of cars, showing circuits of the solenoid and magnetic 75 switches and showing the location of the brake-spindle. Fig. 13 is a diagrammatic view of the wiring of the brake-motor circuits for one car or a series of cars in train and showing the location of the brake- 80 spindle.

Like characters of reference refer to like parts throughout the several views.

The bed-plate A is bolted to the platform-buffer timber A' of a car, and secured to said 85 bed-plate A by suitable bolts is a base-frame or motor-support B.

B' B' are brackets formed on the base-plate A and to which is pivoted the bell-crank lever B².

B³ is an opening formed in the base-frame B to admit the levers B² and B⁶.

B⁴ is a boss on the base-plate A, forming a bearing for the motor-shaft C.

At or near the lower end of the motor-shaft C is a suitable loose gear C', forming part of the clutch member D, and which is adapted to mesh with the gear C², fast on the brake-spindle C³, to the lower end of which is connected the brake-chain C⁴. This brake-spindle is supported and guided by the bearing C⁵, depending from the bed-plate A.

C⁶ is the usual ratchet-wheel, with which the pawl C⁷, operated by the foot of the operator, engages for holding the brakes when 105 set by hand and with the motor-clutch dis-

engaged. Fast on the motor-shaft C is a driving clutch member D', and located in suitable recesses on the exterior of the clutch member D' are two bands of brass D² D³, 5 which are suitably connected to the ends of the magnet-wire D⁴. The circuit-closing bracket E is supported by the upright arm B⁵ of the bell-crank lever E² and carries the upper and lower contact-wheels E' E², suitably insulated from the bracket, as shown, the wheel E² acting as an inlet and the wheel E' acting as an outlet, thereby forming an electric clutch circuit-closer.

E³ is a magnetic solenoid attached to the base-frame, which coöperates with the metal pin B', pivoted on the arm B⁵, and can be actuated when the magnetic wire is energized. The energizing of said wire is accomplished by the switch E⁴ being closed by the operator placing his foot on the inner part of the tread E⁵, which will operate the lever-arm B⁶, pivoted at E⁶ to the lever B². The extreme end E⁷ of the lever-arm B⁶ is insulated, as shown, so as to prevent the current passing off and compel it to pass through the wire 7 into the magnetic solenoid E³ and thence out to the ground by the wire 8. By this operation the upright arm B⁵ of the bell-crank lever B² is pulled away from the magnetic clutch member D', breaking the electric contact on the bands D² D³. This will de-energize the magnetic clutch, allowing the lower clutch member D to separate from the upper member D' by gravity. With the clutch members in this released position the operator can rotate the motor-armature C or allow it to stand still at will. It will be understood that when the mechanism is in this released position the motor is running free and is not acting upon the spindle C³, as no motion is communicated to the gear C'.

The operation of the switch E⁴, as above described, will when suitably connected by the wire-circuit cause the operation of a plurality of motors and spindles on the different cars for train service.

It will be further understood that this operation will release one or all of the brakes by the operation of one or a plurality of motor mechanisms located on one or a plurality of cars comprising a train.

F is an enlarged diameter of the motor base-frame B, forming a socket for the insertion of the lower end of the motor-frame F' and secured by suitable bolts F² and bolts F³, which latter pass through the motor-frame C to the pole-piece F⁴, (see Figs. 5 and 6,) securing all in an assembled position.

G is an extension-frame forming a housing and covering for the entire electric apparatus and secured in a similar manner to the motor-frame by bolts G' G², as the motor-frame is secured to the base-frame B.

H H' are covers for the hand-holes H² H³, formed in the sides of the extension-frame G.

H⁴ represents bolt-holes to receive bolts to fasten the covers to the extension-frame over the hand-holes H² H³.

H⁵ is a boss formed on the under side of the top of the extension-frame G, forming an upper bearing for the motor-armature shaft C.

H⁶ H⁷ are insulating-bushings for the purpose of insulating the brush-holding brackets H⁸.

H⁹ is a metal washer between the bushing H⁷ and the jam-nut H¹⁰, said nut meshing with the thread H¹¹ on the lower end of the boss H⁵. This nut H¹⁰ is used for the purpose of fastening the brush-holding arrangement in a fixed position after the brushes are set. The brush-holding arms J J' are secured to the bracket H⁸. The brushes K K' make contact with the commutator K².

K³ is a cap secured by suitable bolts K⁴ on the top of the extension-frame G. On the upper end of the motor-armature shaft C and within said cap is fixed the ratchet dog or clutch K⁵, engaging with the companion ratchet member or dog K⁶, which is held from rotation by the bolts K⁷ passing through the walls of cap K³, the points of which fit in slots on the companion member K⁶ and allow a vertical movement of said member K⁶. This member K⁶ is held in engagement with the member K⁵ by the spring K⁸, interposed between the under side of the cap K³ and the top of the member K⁶. The ratchet mechanism is for the purpose of holding the motor-shaft from a reverse rotation when the motor-power is cut out in the after application of the brakes from the brake-spring pull with the clutches engaged, but allows the motor-shaft to rotate freely to the left in the application of the brakes while preventing any movement of the motor-shaft to the right.

G³ is a boss on the top of the extension-frame G, forming with the hole G⁴ a guide and bearing for the upper end of the brake-spindle C³.

L is a motor-armature having its armature-shaft provided with extended ends, as shown, which are journaled in the boss B' and boss H⁵.

By the above-described construction the motor-armature is held in place. The loose clutch member D is connected to the gear C', forming part thereof, by means of the throat C⁶, and said member is adapted to a vertical movement on the lower end of the motor-armature shaft C. On the upper end of the brake-spindle C³ is mounted a hand-power handle provided with mechanism to permit the spindle C³ to rotate freely in the chamber M' of said handle when the spindle is driven by motive power without turning the handle M. Normally the handle M is disengaged from the brake-spindle C³. To engage said handle when desired to operate the spindle

by hand-power, the operator, placing his hand on the top of the handle, will depress the plunger M^2 against the resiliency of the spring M^3 , housed in the handle M , and through the rod M^4 a downward pressure will be conveyed to the bell-crank lever M^5 , which is pivoted on the forked bracket M^{10} , formed on the under side of the handle M , causing the other end of the bell-crank lever to move inwardly toward the brake-spindle, pressing on the plunger M^7 , which is driven into one of the orifices M^8 , formed on the fixed hub M^9 of the spindle C^3 , thereby connecting the hand-power handle and the chain-winding spindle C^3 . There are a number of these orifices M^8 in the hub M^9 to permit the pin M^7 to enter at short intervals when it is desired to connect the handle and brake-spindle. To disconnect the handle from the spindle, the operator releases the pressure from the plunger M^2 and springs M^3 , withdraws the pin M^7 from the spindle-hub M^9 , leaving the brake-spindle M^3 free to be revolved without the handle by the motive power.

The motor current-controller N consists of a shaft N' , supported by the brackets N^2 and the bearing N^3 in the frame G , and on its upper end there is mounted the handle N^4 , which can be removed, if desired. This handle N^4 is arranged to rotate the shaft N' against the spring N^5 , secured at one end at N^6 to the frame G and at the other end to the shaft N' at N^7 . Mounted at or near the lower end of the shaft N' is the contact-arm N^8 , which supports the contact-plate N^9 , which is insulated from it by the strip O . Directly opposite on the hub of said arm is formed the quadrant-ratchet circle P , with which co-operates the pawl P' , pivoted on the bracket P^2 by the pin P^3 . The ratchet-circle and the pawl are for the purpose of holding the contact-arm N^8 out of the electric circuit when not in use.

The bracket Q is secured to the frame G by suitable bolts and carries the terminal posts R R' , suitably insulated, as shown, from the bracket Q . The intake-wire I is connected with the post R , and the intake-wire 2 is connected with the post R' , receiving current from the trolley-wire when the contact-plate N^9 covers both, after which the current will flow through the wire 2 , insulated from the post R' , to the motor field-wire 3 , which is a continuation of the wire 2 , and the circuit then passes into the field-coils 4 , Fig. 5, thence to the brush-holding arrangement J' by the wire 5 , thence to the brush K' , to the armature K^2 , and out through the brush K to the brush-holding arm J and out through the wire 6 to the ground.

The operation of rotating the spindle C^3 to wind up the chain C^4 to apply the brakes on one or more cars is as follows: The operator disengages the pawl P' from the quadrant-ratchet circle P from the position shown in Fig. 2, when the spring N^5 will cause the op-

erator to use pressure on the end N^4 to keep the contact-plate N^9 from closing the circuit. At will the operator may release said pressure on the handle N^4 , when the spring N^5 will automatically act to cover the binding-posts R R' by the plate N^9 , which will close the circuit to allow the current to flow from its source across the plate N^9 to the post R' , thence to the wire 2 , to the wire 3 , (which is a continuation of the wire 2), passing through the fields 4 , thence to the wire 5 to the brush-holding arm J' , passing out through the brush K' to the commutator K^2 , through the brush K to the arm J , and to the ground by the wire 6 . This flow of current will rotate the armature L and the extended armature-shafts C , which will rotate the clutch member D' . Now to operate the spindle C^3 to apply the brakes the operator breaks the circuit through the switch E^4 by releasing the pressure on the tread E^5 , and the spring E^8 will then force the insulated part E^7 of the lever B^6 from the switch E^4 , thus breaking the circuit through said switch E^4 , which deenergizes the magnetic solenoid E^3 , and this releases the metal pin B^7 from its magnetic influence, permitting the arm B^6 of the bell-crank lever E^2 to move inwardly by means of the spring E^{10} . This will force into contact the wheels E^1 E^2 with the bands D^2 D^3 . While this operation takes place the end E^7 of the lever B^6 closes the switch E^9 , thereby allowing the current to flow through the wire 9 to the wheel E^2 , to the band D^3 , through the magnetic wire D^4 to the metallic band D^2 , out through the wheel E^1 , thence to the ground by the wire 10 . As explained, the metallic clutch member D' will by its magnetic influence exert an attraction on the lower clutch member D upwardly, bringing into contact the inclined surfaces of each member and holding the clutch in engagement, and thereby rotating the gear C' , which will transmit power to the gear C^2 , fast on the spindle C^3 , rotating said spindle to wind up the chain C^4 and set the brakes. The gear C^2 being of larger diameter than the gear C' causes a multiplication of power in the application of the brakes. If the spring E^8 should become broken or otherwise lose its tension, the operator can press on the outer end of the tread E^5 of the lever B^6 and cause the engagement of the end E^7 with the switch E^9 . With the brakes applied, as above described, the operator can open the motor-circuit, keeping the clutch members engaged, and the brakes will be automatically held by the ratchet or dog mechanism K^5 K^6 , located in the cap K^3 , as shown. When desired to release the brakes, the operator will disengage the clutch members D D' in a manner previously described, allowing the free rotation of the spindle C^3 by the usual brake-spring pull rotating the gear C' in the opposite direction without affecting the other mechanism.

In the diagrammatic view, Fig. 12, there is shown a plurality of solenoids and clutch members in circuit for train-service, and the construction shown is embodied in the braking apparatus on each end of the cars in Figs. 1 to 9. To energize the two solenoids of one car or more in a train, the switch E^4 is closed by the operator, as above described, which closes the circuit through the wire 7 and solenoids E^3 , and the current passes by the wire 8 to the ground. The continuation of the current to the next car is through the wire S' and coupling connection S , thence to the next car connected with the wires 7 and S' through the solenoids E^3 , thence to the wire 8 to the ground. In this manner the operation of the apparatus by the operator at the head of a train releases the brakes by rotating the spindles, due to the usual brake-spring pull throughout the entire train by means of the electromagnetic solenoid-circuit in a manner similar to that previously described for one car.

To apply the brakes by the rotation of the brake-spindles, the switch E^4 is opened, which deenergizes the solenoids, and the switch E^9 is closed, which energizes the magnetic clutch, attracting the clutch members to engagement, which clutch members are rotated by the motor-shaft C , which has been previously put in rotation, as hereinbefore described. The source of current for the wire-circuit for one or all of the clutch members is similar to the solenoid-circuit—that is, the source of supply comes from the wire 7 through the switch E^9 and wire 9 through each upper clutch member D' out to the ground by the wire 10.

The electric circuit for the clutch members for one or a train of cars is by means of the wire T and coupling T' .

Having described the circuits for the solenoid and the clutches, the motor-circuit (shown in diagrammatic view, Fig. 13) will be described. The wiring for the motor-circuit is as follows: The source of supply is from the wire 3, which is a continuation of the wires 1 2, and the manner of starting the motor or motors is by throwing the arm N^8 to cover the posts $R R'$, which will allow current to flow through the motor or motors, as shown by the wiring, and out to the ground by the wires 6. U' is a coupling placed between the cars for train-service and with the wires U carries the current through the train.

It will be understood that the current may be taken from the trolley-wire or from the third rail (which are marked, respectively, TW and TR) or from any source.

As shown in Figs. 10 and 11, the construction of the platform and car-bottom frame consists of buffer-timbers A' , with a platform-flooring b . $c c c c$ are the supporting-timbers, fastened to the body of the car and support-

ing the flooring b and buffer-timber A' . d is 65 the end sill, which is fastened to the extreme end of the side sill e . f represents the bottom-frame cross-timbers, which are fastened to the side sill e to support the flooring. To the end sill d and side sill e the end frame and side 70 frame of the car are secured in the usual manner of car-building. g is the main brake-rod, and at one end of said rod is connected the brake-chain C^4 , and the other end is pivotally connected to the center brake-lever h . The 75 main or center brake-lever h is supported by the bracket i , secured to the bottom of the car, and has an equalizing-slot j . The said brake-lever h is held in place by the pin k . Pivotally connected to the center brake-lever 80 h is the secondary brake-rod l , pivoted at its opposite end to the truck brake-lever m , which is pivoted on the brake-beam p . At the lower end of the brake-lever m is pivotally connected the brake-rod o , which at its 85 opposite end is connected to the truck-adjusting arm n . On the ends of the brake-beams p are fastened the brake-shoes q , which come in contact with the periphery of the wheels r , mounted on the axles s . The 90 brake-rod g and the secondary rod l (shown on the right of Figs. 10 and 11) extend forward and are connected to similar mechanism at the right-hand end of the car. The operation of this mechanism is as follows: 95 By rotating the spindle C^3 and winding up the chain C^4 the brake-rod g will be pulled forward, thereby actuating the brake-lever h . This will pull in the opposite direction the secondary rods l , and by this operation the 100 secondary rods will pull the truck-levers m toward the center of the car, pressing out the bottom end of the levers m toward the end of the car, causing the brake-beams p to travel in the opposite direction, and thereby apply 105 the brake-shoes to the wheels. By the arrangement of the spindle with the brake-handle, as hereinbefore described, the spindle can revolve in either direction without rotating the handle, or the handle can be rotated in either direction without rotating the spindle or motor, or, if desired, the handle can rotate the spindle without rotating the motor or operate both at the same time. To rotate the 110 motor-armature without current, the clutch 115 member D is brought into engagement with the clutch member D' by the foot-lever arrangement, so that by the rotation of the handle when the clutch members are engaged the gear becomes operative from the spindle to the armature-shaft, thereby enabling the same to be rotated.

I do not limit myself to the arrangement and construction shown, as the same may be varied without departing from the spirit of 125 my invention.

Having thus described the nature of my invention and set forth a construction em-

bodging the same, what I claim as new, and desire to secure by Letters Patent of the United States, is—

1. In an apparatus of the character described, a motor - clutch and gear - driven brake-spindle, an electric motor, a rotatable electric - motor - armature shaft, automatic means for closing the motor-circuit to rotate said armature-shaft, and automatic means for transmitting power from said armature-shaft to said brake-spindle for rotating said spindle and independent of said motor-circuit-closing means.

2. In an apparatus of the character described, a motor - clutch and gear - driven brake-spindle, an electric motor, a rotatable electric - motor - armature shaft, means for closing the motor-circuit to rotate said armature-shaft, and automatic means for transmitting power from said armature-shaft to said brake-spindle for rotating said spindle to apply the brakes and independent of said motor-circuit-closing means.

3. In an apparatus of the character described, a motor - clutch and gear - driven brake-spindle, an electric motor, a rotatable electric - motor - armature shaft, automatic means for closing the motor-circuit to rotate said armature-shaft, and means for transmitting power from said armature-shaft to said brake-spindle for rotating said spindle and independent of said motor-circuit-closing means.

4. In an apparatus of the character described, a motor - clutch and gear - driven brake-spindle, an electric motor, a rotatable electric-motor-armature shaft; clutch mechanism for transmitting power from said motor to said spindle, automatic means for closing the motor-circuit, and automatic means for engaging said clutch mechanism to transmit power from said motor to said brake-spindle and independent of said motor-circuit-closing means.

5. In an apparatus of the character described, a motor - clutch and gear - driven brake-spindle, an electric motor, a rotatable electric - motor - armature shaft, clutch mechanism for transmitting power from said motor to said spindle, means for closing the motor-circuit, and automatic means for engaging said clutch mechanism to transmit power from said motor to said brake-spindle and independent of said motor - circuit - closing means.

6. In an apparatus of the character described, a motor - clutch and gear - driven brake-spindle, an electric motor, a rotatable electric - motor - armature shaft, clutch mechanism for transmitting power from said motor to said spindle, automatic means for closing the motor-circuit, and means for engaging said clutch mechanism to transmit power from said motor to said brake - spindle and

independent of said motor - circuit closing means.

7. In an apparatus of the character described, a chain-winding brake-spindle, an electric motor, a rotatable motor - armature shaft, automatic means for closing the motor-circuit to rotate the said armature-shaft, and automatic means for transmitting power from said armature-shaft to said spindle and independent of said motor-circuit-closing means.

8. In an apparatus of the character described, a chain-winding brake-spindle, an electric motor, a rotatable motor - armature shaft, means for closing the motor-circuit to rotate said armature-shaft, and automatic means for transmitting power from said armature-shaft to said spindle and independent of said motor-circuit-closing means.

9. In an apparatus of the character described, a chain-winding brake-spindle, an electric motor, a rotatable motor - armature shaft, automatic means for closing the motor-circuit to rotate said armature-shaft, and means for transmitting power from said armature-shaft to said spindle and independent of said motor-circuit-closing means.

10. In an apparatus of the character described, a motor - clutch and gear - driven brake-spindle, an electric motor, a rotatable electric - motor - armature shaft, automatic means for closing the motor-circuit to rotate said armature-shaft, automatic means for transmitting power from said armature-shaft to said brake-spindle for rotating said spindle and independent of said motor-circuit-closing means, and an electric circuit controlled by said motor-circuit-closing means.

11. In an apparatus of the character described, a motor - clutch and gear - driven brake-spindle, an electric motor, a rotatable electric - motor - armature shaft, automatic means for closing the motor-circuit to rotate said armature-shaft, automatic means for transmitting power from said armature-shaft to said brake-spindle for rotating said spindle and independent of said motor-circuit-closing means, and an electric circuit for controlling said power-transmitting means.

12. In an apparatus of the character described, a motor - clutch and gear - driven brake-spindle, an electric motor, a rotatable electric - motor - armature shaft, automatic means for closing the motor-circuit to rotate said armature-shaft, automatic means for transmitting power from said armature-shaft to said brake-spindle for rotating said spindle and independent of said motor-circuit closing means, an electric circuit controlled by said motor-circuit-closing means, and an electric circuit for controlling said power-transmitting means.

13. In an apparatus of the character described, a motor - clutch and gear - driven brake-spindle, an electric motor, a rotatable

electric - motor - armature shaft, automatic means for closing the motor-circuit to rotate said armature-shaft, automatic means for transmitting power from said armature-shaft to said brake-spindle for rotating said spindle and independent of said motor-circuit-closing means, an electric circuit controlled by said motor-circuit-closing means, and a handle for operating said motor-circuit-closing means to break the motor-circuit.

14. In an apparatus of the character described, a motor-clutch and gear-driven brake-spindle, an electric motor, a rotatable electric-motor-armature shaft, automatic means for closing the motor-circuit to rotate said armature-shaft, automatic means for transmitting power from said armature-shaft to said brake-spindle for rotating said spindle and independent of said motor-circuit-closing means, and an electric solenoid-circuit for controlling said power-transmitting means.

15. In an apparatus of the character described, a motor-clutch and gear-driven brake-spindle, an electric motor, a rotatable electric-motor-armature shaft, automatic means for closing the motor-circuit to rotate said armature-shaft, automatic means for transmitting power from said armature-shaft to said brake-spindle for rotating said spindle and independent of said motor-circuit-closing means, an electric circuit controlled by said motor-circuit-closing means, and an electric solenoid-circuit for controlling said power-transmitting means.

35 16. In an apparatus of the character described, a motor-clutch and gear-driven
brake-spindle, an electric motor, a rotatable
electric-motor-armature shaft, means for closing
the motor-circuit to rotate said armature-
shaft, and means for transmitting power from
40 said armature-shaft to said brake-spindle for
rotating said spindle to apply the brakes and
independent of said motor-circuit-closing
means.

45 17. In an apparatus of the character described, a motor-clutch and gear-driven brake-spindle, an electric motor, a rotatable electric-motor-armature shaft, clutch mechanism for transmitting power from said motor
50 to said spindle, automatic means for closing the motor-circuit, automatic means for engaging said clutch mechanism to transmit power from said motor to said brake-spindle and independent of said motor-circuit-closing means, and an electric circuit controlled by
55 said motor-circuit-closing means.

65 18. In an apparatus of the character described, a motor-clutch and gear-driven
66 brake-spindle, an electric motor, a rotatable
67 electric-motor-armature shaft, clutch mechanism for transmitting power from said motor
68 to said spindle, automatic means for closing
69 the motor-circuit, automatic means for en-
70 gaging said clutch mechanism to transmit
71 power from said motor to said brake-spindle
72

and independent of said motor-circuit-closing means, and an electric circuit for controlling said clutch mechanism.

19. In an apparatus of the character described, a motor-clutch and gear-driven 70
brake-spindle, an electric motor, a rotatable
electric-motor-armature shaft, clutch mechanism
for transmitting power from said motor
to said spindle, automatic means for closing
the motor-circuit, automatic means for en- 75
gaging said clutch mechanism to transmit
power from said motor to said brake-spindle
and independent of said motor-circuit-closing
means, an electric circuit controlled by said
electric-circuit-closing means, and an electric 80
circuit for controlling said clutch mechanism.

20. In an apparatus of the character described, a motor-clutch and gear-driven brake-spindle, an electric motor, a rotatable electric-motor-armature shaft, clutch mechanism for transmitting power from said motor to said spindle, means for closing the motor-circuit, automatic means for engaging said clutch mechanism to transmit power from said motor to said brake-spindle and independent of said motor-circuit-closing means, and an electric circuit controlled by said motor-circuit-closing means. 85 90

21. In an apparatus of the character described, a motor-clutch and gear-driven 95
brake-spindle, an electric motor, a rotatable electric-motor-armature shaft, clutch mechanism for transmitting power from said motor to said spindle, means for closing the motor-circuit, automatic means for engaging said clutch mechanism to transmit power from 100
said motor to said brake-spindle and independent of said motor-circuit-closing means, and an electric circuit for controlling said clutch mechanism. 105

22. In an apparatus of the character described, a motor-clutch and gear-driven brake-spindle, an electric motor, a rotatable electric-motor-armature shaft, clutch mechanism for transmitting power from said motor to said spindle, means for closing the motor-circuit, automatic means for engaging said clutch mechanism to transmit power from said motor to said brake-spindle and independent of said motor-circuit-closing means, an electric circuit controlled by said electric-circuit-closing means, and an electric circuit for controlling said clutch mechanism. 110

23. In an apparatus of the character described, a motor-clutch and gear-driven 12
brake-spindle, an electric motor, a rotatable
electric-motor-armature shaft, means for clos-
ing the motor-circuit to rotate said armature-
shaft, means for transmitting power from
said armature-shaft to said brake-spindle for
rotating said spindle to apply the brakes and
independent of said motor-circuit-closing
means, and an electric circuit controlled by
said motor-circuit-closing means. 12

24. In an apparatus of the character de- 13

- scribed, a motor-clutch and gear-driven 5
brake-spindle, an electric motor, a rotatable
electric-motor-armature shaft; means for closing
the motor-circuit to rotate said armature-
shaft, means for transmitting power from
said armature-shaft to said brake-spindle for
rotating said spindle to apply the brakes and
independent of said motor-circuit-closing
means, and an electric circuit for controlling
10 said power-transmitting means.
25. In an apparatus of the character de-
scribed, a motor-clutch and gear-driven
brake-spindle, an electric motor, a rotatable
electric-motor-armature shaft, means for closing
15 the motor-circuit to rotate said armature-
shaft, means for transmitting power from said
armature-shaft to said brake-spindle for ro-
tating said spindle to apply the brakes and
independent of said motor-circuit-closing
20 means, an electric circuit controlled by said
motor-circuit-closing means, and an electric
circuit for controlling said power-transmit-
ting means.
26. In an apparatus of the character de-
scribed, a motor-clutch and gear-driven
25 brake-spindle, an electric motor, a rotatable
electric-motor-armature shaft, means for closing
the motor-circuit to rotate said armature-
shaft, means for transmitting power from
said armature-shaft to said brake-spindle for
30 rotating said spindle to apply the brakes and
independent of said motor-circuit-closing
means, an electric circuit controlled by said
motor-circuit-closing means, and an electric
35 solenoid-circuit for controlling said power-
transmitting means.
27. In an apparatus of the character de-
scribed, a motor-clutch and gear-driven
brake-spindle, an electric motor, a rotatable
40 electric-motor-armature shaft, clutch mech-
anism for transmitting power from said mo-
tor to said spindle for rotating said spindle to
apply the brakes, means for closing the mo-
tor-circuit, and means for engaging said
45 clutch mechanism to transmit power from
said motor to said brake-spindle and inde-
pendent of said motor-circuit-closing means.
28. In an apparatus of the character de-
scribed, a motor-clutch and gear-driven
50 brake-spindle, an electric motor, a rotatable
electric-motor-armature shaft, means for
closing the motor-circuit to rotate said armature-
shaft, means for transmitting power from
said armature-shaft to said brake-spindle for
55 rotating said spindle and independent of
said motor-circuit-closing means, and
means for disconnecting said brake-spindle
and armature-shaft.
29. In an apparatus of the character de-
60 scribed, a motor-clutch and gear-driven
brake-spindle, an electric motor, a rotatable
electric-motor-armature shaft, automatic
means for closing the motor-circuit to rotate
said armature-shaft, means for transmitting
65 power from said armature-shaft to said
brake-spindle for rotating said spindle and
independent of said motor-circuit-closing
means, and means for disconnecting said
brake-spindle and armature-shaft.
30. In an apparatus of the character de-
70 scribed, a motor-clutch and gear-driven
brake-spindle, an electric motor, a rotatable
electric-motor-armature shaft, means for
closing the motor-circuit to rotate said armature-
shaft, automatic means for transmitting
75 power from said armature-shaft to said brake-
spindle for rotating said spindle and independent
of said motor-circuit-closing means, and
means for disconnecting said brake-spindle
and armature-shaft.
80. 31. In an apparatus of the character de-
scribed, a motor-clutch and gear-driven
brake-spindle, an electric motor, a rotatable
electric-motor-armature shaft, automatic
means for closing the motor-circuit to rotate
85 said armature-shaft, automatic means for
transmitting power from said armature-shaft
to said brake-spindle for rotating said spindle
and independent of said motor-circuit-closing
means, and means for disconnecting said
90 brake-spindle and armature-shaft.
32. In an apparatus of the character de-
scribed, a motor-clutch and gear-driven
95 brake-spindle, an electric motor, a rotatable
electric-motor-armature shaft, clutch mech-
anism for transmitting power from said mo-
tor to said spindle, automatic means for clos-
ing the motor-circuit, automatic means for
100 engaging said clutch mechanism to transmit
power from said motor to said brake-spindle
and independent of said motor-circuit-clos-
ing means, and means for disengaging said
clutch mechanism to disconnect said armature-
105 shaft and brake-spindle.
33. In an apparatus of the character de-
scribed, a motor-clutch and gear-driven
brake-spindle, an electric motor, a rotatable
110 electric-motor-armature shaft, clutch mech-
anism for transmitting power from said mo-
tor to said spindle, means for closing the mo-
tor-circuit, automatic means for engaging
115 said clutch mechanism to transmit power
from said motor to said brake-spindle and
independent of said motor-circuit-closing
means, and means for disengaging said clutch
mechanism to disconnect said armature-
120 shaft and brake-spindle.
34. In an apparatus of the character de-
scribed, a motor-clutch and gear-driven
125 brake-spindle, an electric motor, a rotatable
electric-motor-armature shaft, clutch mech-
anism for transmitting power from said mo-
tor to said spindle, automatic means for clos-
ing the motor-circuit, means for engaging
130 said clutch mechanism to transmit power
from said motor to said brake-spindle and
independent of said motor-circuit-closing
means, and means for disengaging said clutch
mechanism to disconnect said armature-
shaft and brake-spindle.

35. In an apparatus of the character described, a motor - clutch and gear - driven brake-spindle, an electric motor, a rotatable electric-motor-armature shaft, clutch mechanism for transmitting power from said motor to said spindle, means for closing the motor-circuit, means for engaging said clutch mechanism to transmit power from said motor to said brake-spindle and independent of 5 said motor-circuit-closing means, and means for disengaging said clutch mechanism to disconnect said armature-shaft and brake-spindle.

36. In an apparatus of the character described, a chain-winding brake-spindle, an 15 electric motor, a rotatable electric-motor-armature shaft, means for closing the motor-circuit, clutch mechanism for transmitting power from said armature-shaft to said spindle for rotating said spindle to apply the 20 brakes, an electric circuit for energizing said clutch mechanism, and means for closing said clutch-mechanism circuit to energize said clutch mechanism to cause its engagement. 25

37. In an apparatus of the character described, a chain-winding brake-spindle, an 30 electric motor, a rotatable electric-motor-armature shaft, means for closing the motor-circuit, clutch mechanism for transmitting power from said armature-shaft to said spindle for rotating said spindle to apply the 35 brakes, an electric circuit for energizing said clutch mechanism, and automatic means for closing said clutch-mechanism circuit to energize said clutch mechanism to cause its engagement. 40

38. In an apparatus of the character described, a chain-winding brake-spindle, an 45 electric motor, a rotatable electric-motor-armature shaft, means for closing the motor-circuit, clutch mechanism for transmitting power from said armature-shaft to said spindle for rotating said spindle to apply the 50 brakes, an electric circuit for energizing said clutch mechanism, means for closing said clutch-mechanism circuit to energize said clutch mechanism to cause its engagement, and means for breaking said circuit to deenergize said clutch mechanism. 55

39. In an apparatus of the character described, a chain-winding brake-spindle, an 55 electric motor, a rotatable electric-motor-armature shaft, means for closing the motor-circuit, clutch mechanism for transmitting power from said armature - shaft to said spindle, an electric circuit for energizing said clutch mechanism, a clutch-circuit closer in said circuit, and means for closing said 60 clutch-mechanism circuit to cause said circuit-closer to engage with said clutch mechanism and energize the same to engage its members. 65

40. In an apparatus of the character described, a chain-winding brake-spindle, an 70

electric motor, a rotatable electric-motor-armature shaft; means for closing the motor-circuit, clutch mechanism for transmitting power from said armature-shaft to said spindle; an electric circuit for energizing said clutch mechanism, a clutch-circuit closer in said circuit, and automatic means for closing said clutch-mechanism circuit to cause said circuit - closer to engage with said clutch mechanism and energize the same to engage 75 its members. 75

41. In an apparatus of the character described, a chain-winding brake-spindle, an electric motor, a rotatable electric-motor-armature shaft, means for closing the motor-circuit, clutch mechanism for transmitting power from said armature-shaft to said spindle, an electric circuit for energizing said clutch mechanism, a clutch-circuit closer in said circuit, means for closing said clutch-mechanism circuit to cause said circuit-closer to engage with said clutch mechanism and energize the same to engage its members, and means for breaking said circuit to deenergize said clutch mechanism to allow its disengagement. 80

42. In an apparatus of the character described, a chain-winding brake-spindle, an electric motor, a rotatable electric-motor-armature shaft, means for closing the motor-circuit, clutch mechanism for transmitting power from said armature-shaft to said spindle for rotating said spindle to apply the 90 brakes, an electric circuit for energizing said clutch mechanism, a clutch-circuit closer in said circuit, automatic means for closing said clutch-mechanism circuit to cause said circuit-closer to engage with said clutch mechanism and energize the same to engage its members, and means for breaking said circuit to deenergize said clutch mechanism to allow its disengagement. 95

43. In an apparatus of the character described, a chain-winding brake-spindle, an electric motor, a rotatable electric-motor-armature shaft, means for closing the motor-circuit, clutch mechanism for transmitting power from said armature-shaft to said spindle, an electric circuit for energizing said clutch mechanism, a clutch-circuit closer in 100 said circuit, a foot-lever adapted to be operated automatically to close said clutch-mechanism circuit to cause said circuit-closer to engage with said clutch mechanism and energize the same to engage its members and adapted to be actuated by the operator to break said circuit to deenergize said clutch mechanism to allow its disengagement. 105

44. In an apparatus of the character described, a chain-winding brake-spindle, an 110 electric motor, a rotatable electric-motor-armature shaft, means for closing the motor-circuit to rotate said armature-shaft, means for transmitting power from said armature-shaft to said brake-spindle, and mechanism 115

for preventing the backward movement of said armature-shaft.

45. In an apparatus of the character described, a chain-winding brake-spindle, an electric motor, a rotatable electric-motor-armature shaft, means for closing the motor-circuit to rotate said armature-shaft, means for transmitting power from said armature-shaft to said brake-spindle, and ratchet mechanism for preventing the backward movement of said armature-shaft.

46. In an apparatus of the character described, a chain-winding brake-spindle, an electric motor, a rotatable electric-motor-armature shaft, means for closing the motor-circuit, a brake-handle capable of engagement with or disengagement from said brake-spindle, and yielding means for normally preventing engagement of said handle and brake-spindle.

47. In an apparatus of the character described, a chain-winding brake-spindle, an electric motor, a rotatable electric-motor-armature shaft, means for closing the motor-circuit, a brake-handle capable of engagement with or disengagement from said brake-spindle, and a spring for normally preventing engagement of said handle and brake-spindle.

48. In an apparatus of the character described, a motor-clutch and gear-driven brake-spindle, an electric motor, a rotatable electric-motor-armature shaft, automatic means for closing the motor-circuit to rotate said armature-shaft, automatic means for transmitting power from said armature-shaft to said brake-spindle for rotating said spindle and independent of said motor-circuit-closing means, and a brake-handle capable of engagement with or disengagement from said brake-spindle.

49. In an apparatus of the character described, a motor-clutch and gear-driven brake-spindle, an electric motor, a rotatable electric-motor-armature shaft, means for closing the motor-circuit to rotate said armature-shaft, automatic means for transmitting power from said armature-shaft to said brake-spindle for rotating said spindle and independent of said motor-circuit-closing means, and a brake-handle capable of engagement with or disengagement from said brake-spindle.

50. In an apparatus of the character described, a motor-clutch and gear-driven brake-spindle, an electric motor, a rotatable electric-motor-armature shaft, automatic means for closing the motor-circuit to rotate said armature-shaft, means for transmitting power from said armature-shaft to said brake-spindle for rotating said spindle and independent of said motor-circuit-closing means, and a brake-handle capable of engagement with or disengagement from said brake-spindle.

51. In an apparatus of the character described, a motor-clutch and gear-driven brake-spindle, an electric motor, a rotatable electric-motor-armature shaft, clutch mechanism for transmitting power from said motor to said spindle, automatic means for closing the motor-circuit, automatic means for engaging said clutch mechanism to transmit power from said motor to said brake-spindle and independent of said motor-circuit-closing means, and a brake-handle capable of engagement with or disengagement from said brake-spindle.

52. In an apparatus of the character described, a motor-clutch and gear-driven brake-spindle, an electric motor, a rotatable electric-motor-armature shaft, clutch mechanism for transmitting power from said motor to said spindle, means for closing the motor-circuit, automatic means for engaging said clutch mechanism to transmit power from said motor to said brake-spindle and independent of said motor-circuit-closing means, and a brake-handle capable of engagement with or disengagement from said brake-spindle.

53. In an apparatus of the character described, a motor-clutch and gear-driven brake-spindle, an electric motor, a rotatable electric-motor-armature shaft, clutch mechanism for transmitting power from said motor to said spindle, automatic means for closing the motor-circuit, means for engaging said clutch mechanism to transmit power from said motor to said brake-spindle and independent of said motor-circuit-closing means, and a brake-handle capable of engagement with or disengagement from said brake-spindle.

54. In an apparatus of the character described, a chain-winding brake-spindle, an electric motor, a rotatable motor-armature shaft, automatic means for closing the motor-circuit to rotate the said armature-shaft, automatic means for transmitting power from said armature-shaft to said spindle and independent of said motor-circuit-closing means, and a brake-handle capable of engagement with or disengagement from said brake-spindle.

55. In an apparatus of the character described, a chain-winding brake-spindle, an electric motor, a rotatable motor-armature shaft, means for closing the motor-circuit to rotate said armature-shaft, automatic means for transmitting power from said armature-shaft to said spindle and independent of said motor-circuit-closing means, and a brake-handle capable of engagement with or disengagement from said brake-spindle.

56. In an apparatus of the character described, a chain-winding brake-spindle, an electric motor, a rotatable motor-armature shaft, automatic means for closing the motor-circuit to rotate said armature-shaft,

means for transmitting power from said armature-shaft to said spindle and independent of said motor-circuit-closing means, and a brake-handle capable of engagement with or disengagement from said brake-spindle.

57. In an apparatus of the character described, a motor-clutch and gear-driven brake-spindle, an electric motor, a rotatable electric-motor-armature shaft, automatic

means for closing the motor-circuit to rotate said armature-shaft, automatic means for transmitting power from said armature-shaft to said brake-spindle for rotating said spindle and independent of said motor-circuit-closing means,

15 means for closing the motor-circuit controlled by said motor-circuit-closing means, and a brake-handle capable of engagement with or disengagement from said brake-spindle.

58. In an apparatus of the character described, a motor-clutch and gear-driven brake-spindle, an electric motor, a rotatable electric-motor-armature shaft, automatic means for closing the motor-circuit to rotate said armature-shaft, automatic means for

25 transmitting power from said armature-shaft to said brake-spindle for rotating said spindle and independent of said motor-circuit-closing means, an electric circuit for controlling said power-transmitting means, and a brake-handle capable of engagement with or disengagement from said brake-spindle.

59. In an apparatus of the character described, a motor-clutch and gear-driven brake-spindle, an electric motor, a rotatable electric-motor-armature shaft, automatic

35 means for closing the motor-circuit to rotate said armature-shaft, automatic means for transmitting power from said armature-shaft to said brake-spindle for rotating said spindle

40 and independent of said motor-circuit-closing means, an electric circuit controlled by said motor-circuit-closing means, an electric circuit controlling said power-transmitting means, and a brake-handle capable of engagement with or disengagement from said

45 brake-spindle.

60. In an apparatus of the character described, a motor-clutch and gear-driven brake-spindle, an electric motor, a rotatable

50 electric-motor-armature shaft, automatic means for closing the motor-circuit to rotate said armature-shaft, automatic means for transmitting power from said armature-shaft to said brake-spindle for rotating said spindle

55 and independent of said motor-circuit-closing means, an electric circuit controlled by said motor-circuit-closing means, and a handle for operating said motor-circuit-closing means to break the motor-circuit, and a

60 brake-handle capable of engagement with or disengagement from said brake-spindle.

61. In an apparatus of the character described, a motor-clutch and gear-driven brake-spindle, an electric motor, a rotatable

65 electric-motor-armature shaft, automatic

means for closing the motor-circuit to rotate said armature-shaft, automatic means for transmitting power from said armature-shaft to said brake-spindle for rotating said spindle and independent of said motor-circuit-closing means, an electric solenoid-circuit for controlling said power-transmitting means, and a brake-handle capable of engagement with or disengagement from said brake-spindle.

62. In an apparatus of the character described, a motor-clutch and gear-driven brake-spindle, an electric motor, a rotatable electric-motor-armature shaft, automatic means for closing the motor-circuit to rotate said armature-shaft, automatic means for transmitting

80 power from said armature-shaft to said brake-spindle for rotating said spindle and independent of said motor-circuit-closing means, an electric circuit controlled by said

85 motor-circuit-closing means, an electric solenoid-circuit for controlling said power-transmitting means, and a brake-handle capable of engagement with or disengagement from said

35 brake-spindle.

63. In an apparatus of the character described, a motor-clutch and gear-driven brake-spindle, an electric motor, a rotatable electric-motor-armature shaft, means for closing the motor-circuit to rotate said armature-shaft, means for transmitting power from

90 said armature-shaft to said brake-spindle for rotating said spindle and independent of said motor-circuit-closing means, and a brake-handle capable of engagement with or disengagement from said brake-spindle.

64. In an apparatus of the character described, a motor-clutch and gear-driven brake-spindle, an electric motor, a rotatable electric-motor-armature shaft, clutch mechanism for transmitting power from said motor to said spindle, automatic means for closing the motor-circuit, automatic means for

100 engaging said clutch mechanism to transmit power from said motor to said brake-spindle and independent of said motor-circuit-closing means, an electric circuit controlled by

105 said motor-circuit-closing means, and a brake-handle capable of engagement with or disengagement from said spindle.

65. In an apparatus of the character described, a motor-clutch and gear-driven brake-spindle, an electric motor, a rotatable electric-motor-armature shaft, clutch mechanism for transmitting power from said motor to said spindle, automatic means for closing the motor-circuit, automatic means for

110 engaging said clutch mechanism to transmit power from said motor to said brake-spindle and independent of said motor-circuit-closing means, an electric circuit for controlling said

115 clutch mechanism and a brake-handle capable of engagement with or disengagement from said brake-spindle.

66. In an apparatus of the character described, a motor-clutch and gear-driven

ture-shaft, means for transmitting power from said armature-shaft to said brake-spindle for rotating said spindle and independent of said motor-circuit-closing means, 5 means for disconnecting said brake-spindle and armature-shaft, and a brake-handle capable of engagement with or disengagement from said brake-spindle.

76. In an apparatus of the character described, a motor-clutch and gear-driven 10 brake-spindle, an electric motor, a rotatable electric-motor-armature shaft, automatic means for closing the motor-circuit to rotate said armature-shaft, means for transmitting power from 15 said armature-shaft to said brake-spindle for rotating said spindle and independent of said motor-circuit-closing means, means for disconnecting said brake-spindle and armature-shaft, and a brake-handle 20 capable of engagement with or disengagement from said brake-spindle.

77. In an apparatus of the character described, a motor-clutch and gear-driven 25 brake-spindle, an electric motor, a rotatable electric-motor-armature shaft, means for closing the motor-circuit to rotate said armature-shaft, automatic means for transmitting power from 30 said armature-shaft to said brake-spindle for rotating said spindle and independent of said motor-circuit-closing means, means for disconnecting said brake-spindle and armature-shaft, and a brake-handle 35 capable of engagement with or disengagement from said brake-spindle.

78. In an apparatus of the character described, a motor-clutch and gear-driven 40 brake-spindle, an electric motor, a rotatable electric-motor-armature shaft, automatic means for closing the motor-circuit to rotate said armature-shaft, automatic means for transmitting power from 45 said armature-shaft to said brake-spindle for rotating said spindle and independent of said motor-circuit-closing means, means for disconnecting said 50 brake-spindle and armature-shaft, and a brake-handle capable of engagement with or disengagement from said brake-spindle.

79. In an apparatus of the character described, a motor-clutch and gear-driven 55 brake-spindle, an electric motor, a rotatable electric-motor-armature shaft, clutch mechanism for transmitting power from said motor to said spindle, automatic means for closing the motor-circuit, automatic means for 60 engaging said clutch mechanism to transmit power from said motor to said brake-spindle and independent of said motor-circuit-closing means, means for disengaging said clutch mechanism to disconnect said armature-shaft and 65 brake-spindle, and a brake-handle capable of engagement with or disengagement from said spindle.

80. In an apparatus of the character described, a motor-clutch and gear-driven 70 brake-spindle, an electric motor, a rotatable 75

electric-motor-armature shaft, clutch mechanism for transmitting power from said motor to said spindle, means for closing the motor-circuit, automatic means for engaging said clutch mechanism to transmit power from said motor to said brake-spindle and independent of said motor-circuit-closing means, means for disengaging said clutch mechanism to disconnect said armature-shaft and brake-spindle, and a brake-handle capable of engagement with or disengagement from said spindle. 80

81. In an apparatus of the character described, a motor-clutch and gear-driven 85 brake-spindle, an electric motor, a rotatable electric-motor-armature shaft, clutch mechanism for transmitting power from said motor to said spindle, automatic means for closing the motor-circuit, means for engaging said clutch mechanism to transmit power from said motor to said brake-spindle and independent of said motor-circuit-closing means, means for 90 disengaging said clutch mechanism to disconnect said armature-shaft and brake-spindle, and a brake-handle capable of engagement with or disengagement from said brake-spindle. 95

82. In an apparatus of the character described, a motor-clutch and gear-driven 100 brake-spindle, an electric motor, a rotatable electric-motor-armature shaft, clutch mechanism for transmitting power from said motor to said spindle, means for closing the motor-circuit, means for engaging said clutch mechanism to transmit power from said motor to said brake-spindle and independent of 105 said motor-circuit-closing means, means for disengaging said clutch mechanism to disconnect said armature-shaft and brake-spindle, and a brake-handle capable of engagement with or disengagement from said brake-spindle. 110

83. In an apparatus of the character described, a chain-winding brake-spindle, an 115 electric motor, a rotatable electric-motor-armature shaft, means for closing the motor-circuit, clutch mechanism for transmitting power from said armature-shaft to said spindle, an electric circuit for energizing said clutch mechanism, means for closing said clutch-mechanism circuit to energize said 120 clutch mechanism to cause its engagement, and a brake-handle capable of engagement with or disengagement from said brake-spindle. 125

84. In an apparatus of the character described, a chain-winding brake-spindle, an 130 electric motor, a rotatable electric-motor-armature shaft, means for closing the motor-circuit, clutch mechanism for transmitting power from said armature-shaft to said spindle, an electric circuit for energizing said clutch mechanism, automatic means for closing said clutch-mechanism circuit to energize said clutch mechanism to cause its engagement, and a brake-handle capable of en- 135

gagement with or disengagement from said brake-spindle.

85. In an apparatus of the character described, a chain-winding brake-spindle, an electric motor, a rotatable electric-motor-armature shaft, means for closing the motor-circuit, clutch mechanism for transmitting power from said armature-shaft to said spindle, an electric circuit for energizing said clutch mechanism, means for closing said clutch-mechanism circuit to energize said clutch mechanism to cause its engagement, means for breaking said circuit to deenergize said clutch mechanism, and a brake-handle capable of engagement with or disengagement from said brake-spindle.

86. In an apparatus of the character described, a chain-winding brake-spindle, an electric motor, a rotatable electric-motor-armature shaft, means for closing the motor-circuit, clutch mechanism for transmitting power from said armature-shaft to said spindle, an electric circuit for energizing said clutch mechanism, a clutch circuit-closer in said circuit means for closing said clutch-mechanism circuit to cause said circuit-closer to engage with said clutch mechanism and energize the same to engage its members, and a brake-handle capable of engagement with or disengagement from said brake-spindle.

87. In an apparatus of the character described, a chain-winding brake-spindle, an electric motor, a rotatable electric-motor-armature shaft, means for closing the motor-circuit, clutch mechanism for transmitting power from said armature-shaft to said spindle, an electric circuit for energizing said clutch mechanism, a clutch circuit-closer in said circuit, automatic means for closing said clutch-mechanism circuit to cause said circuit-closer to engage with said clutch mechanism and energize the same to engage its members, and a brake-handle capable of engagement with or disengagement from said brake-spindle.

88. In an apparatus of the character described, a chain-winding brake-spindle, an electric motor, a rotatable electric-motor-armature shaft, means for closing the motor-circuit, clutch mechanism for transmitting power from said armature-shaft to said spindle, an electric circuit for energizing said clutch mechanism, a clutch circuit-closer in said circuit, means for closing said clutch-mechanism circuit to cause said circuit-closer to engage with said clutch mechanism and energize the same to engage its members, means for breaking said circuit to deenergize said clutch mechanism to allow its disengagement, and a brake-handle capable of engagement with or disengagement from said brake-spindle.

89. In an apparatus of the character described, a chain-winding brake-spindle, an

electric motor, a rotatable electric-motor-armature shaft, means for closing the motor-circuit, clutch mechanism for transmitting power from said armature-shaft to said spindle, an electric circuit for energizing said clutch mechanism, a clutch circuit-closer in said circuit, automatic means for closing said clutch-mechanism circuit to cause said circuit-closer to engage with said clutch mechanism and energize the same to engage its members, means for breaking said circuit to deenergize said clutch mechanism to allow its disengagement, and a brake-handle capable of engagement with or disengagement from said brake-spindle.

90. In an apparatus of the character described, a chain-winding brake-spindle, an electric motor, a rotatable electric-motor-armature shaft, means for closing the motor-circuit, clutch mechanism for transmitting power from said armature-shaft to said spindle, an electric circuit for energizing said clutch mechanism, a clutch circuit-closer in said circuit, a foot-lever adapted to be operated automatically to close said clutch-mechanism circuit to cause said circuit-closer to engage with said clutch mechanism and energize the same to engage its members and adapted to be actuated by the operator to break said circuit to deenergize said clutch mechanism to allow its disengagement.

91. In an apparatus of the character described, a chain-winding brake-spindle, an electric motor, a rotatable electric-motor-armature shaft, means for closing the motor-circuit to rotate said armature-shaft, means for transmitting power from said armature-shaft, means for closing the motor-circuit to rotate said armature-shaft, means for transmitting power from said armature-shaft to said brake-spindle, mechanism for preventing the backward movement of said armature-shaft, and a brake-handle capable of engagement with or disengagement from said brake-spindle.

92. In an apparatus of the character described, a chain-winding brake-spindle, an electric motor, a rotatable electric-motor-armature shaft, means for closing the motor-circuit to rotate said armature-shaft, means for transmitting power from said armature-shaft to said brake-spindle, ratchet mechanism for preventing the backward movement of said armature-shaft, and a brake-handle capable of engagement with or disengagement from said brake-spindle.

93. In an apparatus of the character described, a chain-winding brake-spindle, an electric motor, a rotatable electric-motor-armature shaft, means for closing the motor-circuit, clutch mechanism for transmitting power from said armature-shaft to said spindle, an electric circuit for energizing said clutch mechanism, a clutch circuit-closer in said circuit, a foot-lever adapted to be op-

erated automatically to close said clutch-mechanism circuit to cause said circuit-closer to engage with said clutch mechanism and energize the same to engage its members and adapted to be actuated by the operator to break said circuit to deenergize said clutch mechanism to allow its disengagement, and a brake-handle capable of engagement with or disengagement from said brake-spindle.

94. In an apparatus of the character described, a chain-winding brake-spindle, an electric motor, a rotatable electric-motor-armature shaft, a circuit-closer for said motor-circuit, a spring acting on said circuit-closer and normally tending to close the circuit, a handle for controlling the movement of said circuit-closer, clutch mechanism for transmitting power from said armature-shaft to said spindle, an electric circuit for energizing said clutch mechanism, a clutch circuit-closer in said circuit, and a foot-lever adapted to be operated automatically to close said clutch-mechanism circuit to cause said circuit-closer to engage with said clutch mechanism and energize the same to engage its members and adapted to be actuated by the operator to break said clutch-mechanism circuit to deenergize said clutch mechanism to allow its disengagement.

95. In an apparatus of the character described, a chain-winding brake-spindle, an electric motor, a rotatable electric-motor-armature shaft, a circuit-closer for said motor-circuit, a spring acting on said circuit-closer and normally tending to close the circuit, a handle for controlling the movement of said circuit-closer, clutch mechanism for transmitting power from said armature-shaft to said spindle, an electric circuit for energizing said clutch mechanism, a clutch circuit-closer in said circuit, a foot-lever adapted to be operated automatically to close said clutch-mechanism circuit to cause said circuit-closer to engage with said clutch mechanism and energize the same to engage its members and adapted to be actuated by the operator to break said clutch-mechanism circuit to deenergize said clutch mechanism to allow its disengagement, and a brake-handle capable of engagement with or disengagement from said brake-spindle.

96. In an apparatus of the character described, a chain-winding brake-spindle, an electric motor, a rotatable electric-motor-armature shaft, a circuit-closer for said motor-circuit, a spring acting on said circuit-closer and normally tending to close the circuit, a handle for controlling the movement of said circuit-closer, clutch mechanism for transmitting power from said armature-shaft to said spindle, an electric circuit for energizing said clutch mechanism, a clutch circuit-closer in said circuit, a lever carrying said clutch circuit-closer, a foot-lever pivoted on

said clutch-circuit-closer lever, and means for automatically operating said foot-lever to close said clutch-mechanism circuit to cause said circuit-closer to engage with said clutch mechanism and energize the same to engage its members, the said foot-lever being adapted to be actuated by the operator to break said clutch-mechanism circuit to deenergize said clutch mechanism to allow its disengagement.

97. In an apparatus of the character described, a chain-winding brake-spindle, an electric motor, a rotatable electric-motor-armature shaft, a circuit-closer for said motor-circuit, a spring acting on said circuit-closer and normally tending to close the circuit, a handle for controlling the movement of said circuit-closer, clutch mechanism for transmitting power from said armature-shaft to said spindle, an electric circuit for energizing said clutch mechanism, a clutch circuit-closer in said circuit, a lever carrying said clutch circuit-closer, a foot-lever pivoted on said clutch-circuit-closer lever, means for automatically operating said foot-lever to close said clutch-mechanism circuit to cause said circuit-closer to engage with said clutch mechanism and energize the same to engage its members, the said foot-lever being adapted to be actuated by the operator to break said clutch-mechanism circuit to deenergize said clutch mechanism to allow its disengagement, and a brake-handle capable of engagement with or disengagement from said brake-spindle.

98. In an apparatus of the character described, a chain-winding brake-spindle, an electric motor, a rotatable electric-motor-armature shaft, a circuit-closer for said motor-circuit, a spring acting on said circuit-closer and normally tending to close the circuit, a handle for controlling the movement of said circuit-closer, clutch mechanism for transmitting power from said armature-shaft to said spindle, an electric circuit for energizing said clutch mechanism, a clutch circuit-closer in said circuit, a pivoted bell-crank lever carrying said clutch circuit-closer, a foot-lever pivoted on said clutch-circuit-closer lever, and means for automatically operating said foot-lever to close said clutch-mechanism circuit to cause said circuit-closer to engage with said clutch mechanism and energize the same to engage its members, the said foot-lever being adapted to be actuated by the operator to break said clutch-mechanism circuit to deenergize said clutch mechanism to allow its disengagement.

99. In an apparatus of the character described, a chain-winding brake-spindle, an electric motor, a rotatable electric-motor-armature shaft, a circuit-closer for said motor-circuit, a spring acting on said circuit-closer and normally tending to close the circuit, a handle for controlling the movement of said

5 circuit-closer, clutch mechanism for transmitting power from said armature-shaft to said spindle, an electric circuit for energizing said clutch mechanism, a clutch circuit-closer in said circuit, a pivoted bell-crank lever carrying said clutch circuit-closer, a foot-lever pivoted on said clutch-circuit-closer lever, means for automatically operating said foot-lever to close said clutch-mechanism circuit to cause said circuit-closer to engage with said clutch mechanism and energize the same to engage its members, the said foot-lever being adapted to be actuated by the operator to break said clutch-mechanism circuit to deenergize said clutch-mechanism to allow its disengagement, and a brake-handle capable of engagement with or disengagement from said brake-spindle.

100. In an apparatus of the character described, a chain-winding brake-spindle, an electric motor, a rotatable electric-motor-armature shaft, a circuit-closer for closing the motor-circuit to rotate said armature-shaft, clutch mechanism for transmitting power from said armature-shaft to said brake-spindle, and mechanism for preventing the backward movement of said armature-shaft upon the disengagement of said clutch mechanism and the release of the brakes.

101. In an apparatus of the character described, a chain-winding brake-spindle, an electric motor, a rotatable electric-motor-armature shaft, a circuit-closer for closing the motor-circuit to rotate said armature-shaft, clutch mechanism for transmitting power from said armature-shaft to said brake-spindle, and ratchet mechanism for preventing the backward movement of said armature-shaft upon the disengagement of said clutch mechanism and the release of the brakes.

102. In an apparatus of the character described, brake mechanism for applying and releasing the brakes, a prime-moving motor for operating said brake mechanism, and a magnetic clutch for connecting the brake mechanism with the motor for applying the brakes and for disconnecting the motor from the brake mechanism for releasing the brakes.

103. In an apparatus of the character described, brake mechanism for applying and releasing the brakes, a chain-winding spindle included in said brake mechanism, a motor for operating said spindle, a magnetic clutch for connecting the shaft of said motor with said spindle for applying the brakes and for disconnecting the shaft of said motor from said spindle for releasing the brakes, and means for controlling the operation of said clutch.

104. In an apparatus of the character described, brake mechanism for applying and releasing the brakes, a chain-winding spindle included in said brake mechanism, a motor for operating said spindle, an electric magnetic clutch for connecting the shaft of said

motor with said spindle for applying the brakes and for disconnecting the shaft of said motor from said spindle for releasing the brakes, and electric means for controlling the operation of said clutch.

105. In an apparatus of the character described, brake mechanism for applying and releasing the brakes, a motor for operating said brake mechanism, a clutch for connecting the brake mechanism with said motor for applying the brakes and for disconnecting the motor from the brake mechanism for releasing the brakes, a controller for said clutch, and a spring for moving said controller to energize the clutch for applying the brakes.

106. In an apparatus of the character described, brake mechanism for applying and releasing the brakes, a motor for operating said brake mechanism, a clutch for connecting the brake mechanism with said motor for applying the brakes and for disconnecting the motor from the brake mechanism for releasing the brakes, a controller for said clutch, a spring for moving said controller to energize the clutch for applying the brakes, actuating means for said controller, and a foot-lever additional to said actuating means for operating said controller.

107. In an apparatus of the character described, electrically-operated brake mechanism, means for controlling the operation of the brake mechanism, a spring for moving said controlling means for closing the circuit through the motor to set the brakes, and locking mechanism for holding said controlling means in position to release the brakes.

108. In an apparatus of the character described, a chain-winding brake-spindle, an electric motor, a rotatable electric-motor-armature shaft, means for closing the motor-circuit to rotate said armature-shaft, engaging mechanism for transmitting power from said armature-shaft to said brake-spindle and adapted upon engagement to prevent the backward rotation of the brake-spindle when the power is cut out, and mechanism for preventing the backward movement of said armature-shaft.

109. In an apparatus of the character described, a chain-winding brake-spindle, an electric motor, a rotatable electric-motor-armature shaft, means for closing the motor-circuit to rotate said armature-shaft, engaging mechanism for transmitting power from said armature-shaft to said brake-spindle and adapted upon engagement to prevent the backward rotation of the brake-spindle when the power is cut out and upon disengagement to allow the backward rotation of said brake-spindle, and mechanism for preventing the backward movement of said armature-shaft.

110. In an apparatus of the character described, a chain-winding brake-spindle, an

electric motor, a rotatable electric-motor-armature shaft, means for closing the motor-circuit to rotate said armature-shaft, engaging mechanism for transmitting power from said armature-shaft to said brake-spindle and adapted upon engagement to rotate the brake-spindle in one direction and upon disengagement to allow the rotation of the brake-spindle in the opposite direction with the current on the motor, and mechanism for preventing the backward movement of said armature-shaft.

111. A power-brake consisting of an electric motor with extended armature-shaft and provided with mechanical dog that will per-

mit the shaft to rotate but one way, a separate chain-winding shaft, gears interposed between the motor-shaft and chain-winding shaft for transmission of power, and clutch mechanism for the coupling and uncoupling of the motor-shaft and the chain-winding brake-shaft.

In testimony whereof I have signed my name to this specification, in the presence of two subscribing witnesses, this 29th day of October, A. D. 1904.

LOUIS PFINGST.
